UNITED STATES PATENT OFFICE.

CHARLES WHITE AND GEORGE WHITE, OF WASHINGTON, D. C.

TURN-TABLE.

SPECIFICATION forming part of Letters Patent No. 244,703, dated July 19, 1881.

Application filed May 24, 1881. (No model.)

To all whom it may concern:

Be it known that we, CHARLES WHITE and GEORGE WHITE, citizens of the United States, residing at Washington, District of Columbia, 5 have invented certain new and useful Improvements in Turn-Tables; and we do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

This invention relates to that class of turn-tables which are used for turning horse-cars; and the nature thereof is in providing a certain construction for the purpose of preventing the wear at the pivot; also, in cone-rollers operating upon an independent frame; also, 15 in the construction of the cast well or foundation-plate for the cone-rollers to work on, all of which is hereinafter more fully described.

Referring to the drawings and letters of reference marked thereon, Figure 1 is a sectional side elevation of the improved turn-table. Fig. 2 is a plan of the top of the turn-table. Fig. 3 is an inverted plan of the well or foundation-plate, showing the spokes; Fig. 4, plan view of a portion of the roller-frame. Fig. 5 is an 25 enlarged sectional elevation of the pivot and its connections. Fig. 6 is a plan of the collar-plate, which is bolted to the surface turn-table on the under side. Fig. 7 is a plan of the standard which supports and receives the steel pivot. Fig. 8 is a plan showing the face of the 30 steel pivot, also a cross-section of the steel pivot enlarged. Fig. 9 represents one of the arms of the independent spider-frame and the position of the journal for the cone-roller.

40 In the drawings similar letters of reference indicate corresponding parts.

The bed or foundation plate A' of the turn-table A is made with the projecting arms A² and the outer rim, A³, this rim being of sufficient depth for the purpose of sinking it and its interior work into the ground, so that the upper surface of the rim may be flush with the surface of the ground.

On the arms A² is cast the ring A⁴, which 45 has a bevel face for the rollers to revolve or

run on. The ring A³ is the rim of the foundation-plate. A⁴ is designed for the purpose of allowing the cone-rollers D⁴ to revolve thereon, and to comply with that law which is the law of cones. (Shown by the dotted line m m.) 55 The face of the ring A⁴ is beveled at A⁵ to conform to the lines m m.

The center of the foundation-plate A' may be either square or round, and is provided with a recess, A⁶, into which is placed the pivot-standard B. This pivot-standard is bolted into position in the recess A⁶, and hot lead is poured around so as to firmly close the joints. The pivot-standard B is turned round and true from the base b to top b', and in the top is a 60 square hole or aperture, b², into which is placed a steel pivot-point, C.

Around the lower portion of the pivot-standard B is placed the independently-revolving spider-frame D. This frame D has as many 65 arms D' as may be desirable, and they are linked together by links D². Near the inner end the arms D' are bolted to a central casting, D³, and this part of the casting of the frame D is the part that revolves around the standard B. 70

At the outer ends of the arms D' are the cone-rollers D⁴. These cone-rollers D⁴ rest upon the ring and support the turn-table face-plate E, having a beveled face, E². On the under 75 side of the turn-table face-plate E is bolted the collar-plate E', and this collar-plate E' is of sufficient depth at e to allow this part e to overlap upon the pivot-standard B—that is, when the plate E is resting on the cone-rollers D⁴ 80 their diameter is so arranged that the collar-plate E' shall overlap the pivot-standard B, and thereby act as the point or collar to retain the plate E in position and allow it to revolve 85 on the pivot-standard B. 90

In the projection e of the collar-plate E' is placed the flat turned steel plate F. This plate rests upon the steel pivot-point C, and is held down on that point by a set-screw, G, in the face-plate E. 95

Underneath the steel pivot C are placed, when desired, washers C'. These washers regulate the length of the projection of the steel pivot C, and can be made to take up or provide for the wear and tear of the pivot-point C. Suitable 100

stops can be provided in the rim A³ and in the face-plate E, for the purpose of retaining the turn-table in the proper position to allow a car to run on and to stop the turn-table when 5 the car is either completely turned round or to the right or left, as the case may be.

The operation of the invention is well understood. A car is run on the turn-table, and by revolving the face-plate the car is turned. The 10 weight is very equally distributed on the conical rollers D⁴, and by complying with the geometrical lines m m we cause the turn-table to revolve very easily and freely.

Having thus described the construction and 15 operation of our invention, what we claim as new, and desire to secure by Letters Patent of the United States, is as follows:

1. In a turn-table provided with an independent roller or spider frame and foundation-

plate with pivot-center, the independent pivot- 20 center, substantially as herein shown.

2. The combination, in a turn-table face-plate, E, of the collar-plate E' and set-screw operating on the plate, and pivot-point C in standard B, on and around which they revolve, 25 substantially for the purpose set forth.

3. In a pivot-standard, B, the square recess for the pivot-point, provided with a pivot, C, having washers or taking-up wearing parts, for the purpose set forth. 30

In testimony whereof we affix our signatures in presence of two witnesses.

CHARLES WHITE.
GEORGE WHITE.
